UNITED STATES PATENT OFFICE.

WILLIAM H. HEULINGS, JR., OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

GATE FOR PASSENGER-CARS.

No. 902,489.

Specification of Letters Patent.

Patented Oct. 27, 1908.

Application filed August 18, 1908. Serial No. 449,144.

To all whom it may concern:

Be it known that I, WILLIAM H. HEULINGS, Jr., a citizen of the United States, residing in Philadelphia, Pennsylvania, have 5 invented certain Improvements in Gates for Passenger-Cars, of which the following is a specification.

One object of my invention is to provide mechanism for operating the gate and a step 10 at the side of the platform of a passenger car so that when the gate is closed the step will be moved out of position, and when the gate is opened the step will be moved into position.

15 A further object of the invention is to so design the gate that when open it will form a guard or partition dividing the platform so as to form two passageways, and when the car is of the type in which the passenger 20 pays the fare upon entering the car, one of these passageways may be the ingress passageway, and the other the egress passageway, and the gate in this instance may form a continuation of a partition rail.

25 In the accompanying drawings:—Figure 1, is a sectional plan view of sufficient of a platform of a passenger car to illustrate my invention, showing the gate in the closed position; Fig. 2, is a view similar to Fig. 1, 30 showing the gate in the open position; Fig. 3, is a side view of the gate illustrated in Fig. 1; Fig. 4, is a sectional view on the line 4—4, Fig. 3; and Fig. 5, is a perspective view of the gate locking mechanism which 35 I prefer to use.

A is the body of the car, B is the platform separated from the body of the car by the transverse partition C, having the usual passageways therein.

40 B' is the vestibule casing inclosing the rear of the platform.

D is the gate which is adapted to close one side of the platform, the other side of the platform being closed by a suitable gate 45 or door, as desired. The gate D is arranged to turn and slide upon a vertical pivot standard E extending from the floor of the platform to the frame work of the overhanging portion of the car roof. In order to 50 allow the gate to slide upon the pivot standard as well as turn upon it so as to throw the gate back on to the platform to prevent it from projecting too great a distance beyond the side of the car, I secure two 55 frames d at the upper end or edge of the

gate, and these frames are so formed as to provide a slot of a width equal to the diameter of the standard E, the base e of the standard supporting the gate at the center, and a caster d² in the present instance supports the gate at one end so that the gate can swing and slide freely on the pivot standard.

In order to retract the gate as it is turned on the pivot, I provide a vertical shaft F to 65 which is attached an arm f, and this arm extends to a handle d³ at one end of the gate, as clearly shown in the drawings, so that when the handle d³ is grasped by the conductor the difference in the position of the shaft F and the standard E will cause the gate D to be forced back as it turns on the pivot standard E; as will be readily seen on referring to Fig. 2 of the drawings, so that while the gate extends a trifle beyond 75 the line of the step it does not project far enough to be struck by passing vehicles.

It will be understood that the gate may be projected more or less according to the position of the shaft F in respect to the standard E.

The arm f is firmly attached to the shaft F, so that the shaft must turn with it, and this movement of the shaft is utilized to operate the step. This is accomplished in 85 the following manner: The shaft extends through the floor of the platform and has at its lower end a bevel wheel g which meshes with a bevel wheel g' on a shaft G, and on this shaft are two arms g² which are connected by links g³ to arms i projecting from the step I which is pivoted at i' to brackets J secured to the framework B² of the platform B, in the present instance.

When the gate is closed, as shown in Fig. 95 1, the step I is raised as shown in Fig. 4, so that a passenger cannot try to board the car as the step is not in the proper position; but when the gate is swung to the position shown in Fig. 2, the shaft F is turned and motion 100 will be imparted to the shaft G which will cause the step to assume the position shown so that a passenger can mount the step and enter the car.

I prefer to lock the gate in its closed position, and to accomplish this I provide the shaft F with a toothed segment n with which 105 engages a bolt m adapted to a slot b in the platform, and this bolt is attached to one arm m' of a lever M pivoted to a stud m² on 110

a bracket M' attached to the underside of the platform, the other arm M^2 of the lever being connected to a push rod p which projects through the floor of the car, and has a 5 button which can be pressed by the foot of the conductor.

The teeth of the segment n are ratchet teeth, and the bolt is thrown forward by a spring q , so that while the gate is free to 10 be moved from the open to the closed position, it cannot be opened without first depressing the push rod p which withdraws the bolt m from engagement with the ratchet teeth n . Other forms of locks may be provided without departing from the essential 15 features of the invention.

Thus it will be seen that I provide means for simultaneously opening and closing a gate, and operating a step at the side of the 20 platform at which the gate is mounted, and I also provide means for moving the gate back from the side of the platform as it is opened so it will not project too far beyond the line of the car.

25 I claim:

1. The combination of a platform of a passenger car, a gate at the side of the car, a pivot for the gate, said gate being adapted to turn and slide upon the pivot, with a 30 movable step, and means connecting the step with the gate so that as the gate is opened or closed the step will be moved into and out of position.

2. The combination of a platform of a 35 passenger car, a gate at the entrance to the platform, a pivot standard, the gate being slotted to receive the standard, so that it can turn on and slide upon the pivot standard, with means for causing the gate to be 40 retracted as it is moved from the closed to the open position.

3. The combination of a car platform, a pivot standard at the side of the platform, a gate pivoted to the standard so that when 45 in the open position there will be a passageway on each side of the gate, said gate being capable of sliding upon as well as turning on the pivot, a vertical shaft situated at one side of the pivot standard, an arm connected 50 to the shaft and to the gate some distance from its pivot, so that when the gate is turned the arm will cause it to slide as well as to turn on the pivot.

4. The combination of a platform of a car, 55 a vertical pivot standard, a gate mounted on the standard so as to turn and slide thereon, a shaft at one side of the pivot standard, an arm secured to the shaft and pivoted to the gate some distance from the pivot standard, 60 a pivoted step, and mechanism between the step and the shaft so that, on moving the gate from the closed to the open position, the step will be actuated.

5. The combination of a car platform, a vertical pivot standard, a gate mounted on 65 the standard so as to turn thereon and capable of a limited sliding movement, a vertical shaft at one side of the pivot standard, an arm secured to the shaft and attached to the gate some distance from its 70 pivot point, a shaft under the platform and geared to the vertical shaft, a pivoted step, and arms on the last mentioned shaft connected to the step so that the said step will be raised and lowered on the movement of 75 the gate.

6. The combination of a platform, a pivot standard near the edge of the platform, a gate having a slotted portion through which 80 the pivot standard extends, the standard being in such position that when the gate is moved to its open position there will be a passageway at each side of it, a vertical shaft situated further from the edge of the platform than the pivot standard, and an arm 85 attaching the shaft to the gate so that as the gate is turned the shaft will cause it to be retracted.

7. The combination of a platform, a pivot standard near the edge of the platform, a 90 gate having a slotted portion through which the pivot standard extends, the standard being in such position that when the gate is moved to its open position there will be a passageway at each side of it, a vertical shaft 95 situated further from the edge of the platform than the pivot standard, and an arm attaching the shaft to the gate so that as the gate is turned the shaft will cause it to be retracted so as not to project a great distance beyond the edge of the platform, said vertical shaft extending through the platform, a longitudinal shaft geared to the vertical shaft and having arms, a longitudinal 100 pivoted step also having arms, links attaching the arms of the step to the arms of the shaft so that as the gate is turned to the open or closed position, the step will be lowered or raised.

8. The combination of a platform of a car, 110 a gate, a pivot therefor, said gate being adapted to slide on the pivot, a vertical shaft, an arm on the shaft attached to the gate some distance from its pivot, a segment having ratchet teeth and attached to the shaft, a bolt engaging the teeth of the segment, and 115 a foot-operated pin connected to the bolt, said bolt locking the gate in its closed position.

In testimony whereof, I have signed my 120 name to this specification, in the presence of two subscribing witnesses.
